US00D970559S

(12) **United States Design Patent** (10) Patent No.: **US D970,559 S**
(45) Date of Patent: **** Nov. 22, 2022**

(54) **HYDRAULIC PUMP**

- (71) Applicant: **Danfoss Power Solutions (Zhejiang) Co. Ltd.**, Zhejiang (CN)
- (72) Inventors: **Zhimin Guo**, Zhejiang (CN); **Xiaogang Wang**, Zhejiang (CN); **Gang Chen**, Zhejiang (CN); **Shujun Shen**, Zhejiang (CN); **Hui Jin**, Zhejiang (CN)
- (73) Assignee: **Danfoss Power Solutions (Zhejiang) Co. Ltd.**, Zhejiang (CN)

(**) Term: **15 Years**

(21) Appl. No.: **29/820,249**

(22) Filed: **Dec. 21, 2021**
